(57) **CLAIM**

The ornamental design for a TV receiver, as shown and described.

DESCRIPTION

FIG. 1 is a front, right side, perspective view of a TV receiver showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front, right side, perspective view of a TV receiver including the 1-1 line thereof; and,
FIG. 9 is a cross-section view of the 1-1 line in FIG. 8. The broken lines indicate unclaimed portion of the article that form no part of the claimed design.
